UNITED STATES PATENT OFFICE.

JAMES R. FINLEY, OF DELPHI, INDIANA, ASSIGNOR TO HIMSELF AND
JOHN CARLL, OF SAME PLACE.

WHIFFLETREE-CLIP.

SPECIFICATION forming part of Letters Patent No. 244,967, dated July 26, 1881.

Application filed May 4, 1881. (No model.)

To all whom it may concern:

Be it known that I, JAMES R. FINLEY, of Delphi, in the county of Carroll and State of Indiana, have invented certain new and useful 5 Improvements in Whiffletree-Clips; and I do hereby declare that the following is a full, clear, and exact description thereof, reference being had to the accompanying drawings, and to the letters of reference marked thereon, which form 10 part of this specification, in which—

Figure 1 is a perspective, and Fig. 2 a view showing the ferrule in section and a side elevation of the single-tree.

The objects I have in view are to cheapen 15 the ironing of single-trees and provide such means for securing the trace-hook thereto that the two parts may not become disconnected.

My invention consists in providing the single-tree with a ferrule having lugs between which 20 the ring of the hook is placed, and thus preventing the hook becoming detached from the single-tree, all as will be hereinafter more fully set forth.

To enable others skilled in the art to avail 25 themselves of the benefits arising from my invention, I will now describe its construction and operation.

A represents the single-tree, and B the ferrule, which is formed or cast with lugs d d. 30 These lugs should be located near the inner end of the ferrule, as fully shown in the drawings.

e represents a screw by means of which the ferrule is secured on the end of the single-tree.

C is a hook formed with a ring at its opposite end. This ring is of sufficient diameter 35

to reach from the bottom of the slot between the lugs d d obliquely to the lower inner end of the ferrule, as seen in Fig. 2. Thus when properly adjusted in place it will there be confined and prevented from sliding or slipping 40 either to the right or left. The end of the hook may be bent inward, as usual, in order to prevent the trace from becoming easily detached therefrom.

After the ferrule B has been constructed as 45 described, and before it is screwed to the single-tree, I slip the ring-hook between the lugs, after which the ferrule is fitted on the end of the single-tree and the screw e inserted, as shown in Fig. 2. Thus it will be seen that in 50 the event of the single-tree breaking the ferrule may be easily removed and fitted to a new one.

Having thus fully described my invention, what I claim, and desire to secure by Letters 55 Patent, is—

The combination, with a whiffletree, of the removable ferrule B, having lugs d d cast or formed thereon near its inner end, and the hook C, for connecting the whiffletree to the 60 trace, formed with a ring at its opposite end to encircle the ferrule between the lugs, all substantially as and for the purpose set forth.

In testimony that I claim the foregoing as my own invention I affix my signature in presence of two witnesses.

JAMES R. FINLEY.
